UNITED STATES PATENT OFFICE.

JOHN G. WINTJEN, OF MOUNT VERNON, NEW YORK.

SMOKING PIPE.

Application filed June 28, 1924. Serial No. 722,884.

To all whom it may concern:

Be it known that I, JOHN G. WINTJEN, a citizen of the United States of America, residing at 23 South Ninth Avenue, Mount 50 Vernon, New York, have invented a new and useful Smoking Pipe, of which the following is a specification:

My invention relates to a smoking pipe and more particularly to one in which the 10 stem joins the bowl portion at or near the open upper end thereof.

It is an object of the invention to provide a smoking pipe with novel means for conducting away and receiving liquid or semi- 15 liquid matter entering through the pipe stem or from the pipe bowl.

It is a further object to provide a pipe in which the passage or passages most likely to contain accumulations of tarry matter may 20 be readily cleaned.

It is still another object to provide a novel form of lining for a pipe passage whereby the lining may be removed and cleaned.

The invention will be described in connection with the accompanying illustrative drawings, forming a part of this specification and in which:

Fig. 1 is a partial sectional view of a pipe embodying features of my invention.

Fig. 2 is a fragmentary bottom plan view of the pipe shown in Fig. 1, the lower part being removed.

Fig. 3 is an enlarged perspective view of a tubular member forming a part of my invention.

In said drawings, 5 indicates a pipe bowl member, having the chamber or bowl 6 for receiving tobacco. In the form shown, the stem 7 is integrally formed with the bowl member and joins the latter at or near the upper open end thereof. If desired any suitable form of mouth piece 8 may be attached to the stem 7.

A passage 9 extends through the stem 7 and joins a passage 10, formed in the bowl member and in the present disclosure, this passage 10 is substantially vertical or longitudinal of the bowl member. A short connecting passage 11 connects the interior of the bowl with the passage 10, so that free communication is maintained to permit the pipe to draw.

A tubular member 12, preferably of metal, is inserted in the passage 10 from below and 55 fits rather snugly therein. The inner or

upper end of the tube 12 preferably abuts the inner end of the passage 9 and this end may be cut away as indicated at 13 to afford proper communication between the passage 9 and the interior of the tube while the lower end of the tubular member is in communication with the short passage 11 through a suitable opening 14 formed in the tube for that purpose. Means, such as a flange 15 may be formed on the lower end of the tube member 12, so as to provide a convenient lug to be engaged by the finger or any suitable tool to render withdrawal of the tube easy. The flange 15 preferably extends from only one side of the tube for a purpose to be later described.

A reservoir for liquid is provided at the lower end of the bowl and in the form shown this reservoir is formed in what may be called a catch basin member 16, which is held on the bottom of the bowl member 5 by any suitable means such as screw-threads shown. This reservoir or catch basin is in free communication with the lower end of the passage 10 and also, of course, with the lower end of the tube 12. When the tube 12 is in place and the basin is placed on the end of the bowl member, the flange 15 by engagement with the inner edge of the catch basin member will prevent undue rotation of the tube in the passage 10 and thus assure constant open communication between the bowl and the tube. If desired, some form of absorbent material 17 may be placed in basin member 16 to absorb liquid.

When the pipe is in use, liquid or semi-fluid matter such as tar and the like settles out or condenses on the interior of the tube 12. It also often happens that saliva passes down through the stem passage 9 and into the tube 12. By means of my improved construction, this saliva and foul tarry matter is not again drawn into the mouth but passes through the tube to the catch basin 16 communicating with the open lower end thereof. This feature of improvement provides for a clean, cool, dry smoke.

Whenever it becomes necessary to clean the pipe, it is only necessary to remove the catch basin 16 and clean out the accumulation of liquid or tarry matter and the catch basin may then be replaced. If the tubular member 12 should become clogged with accumulated matter which will not flow down into the catch basin, the latter may be re-

moved and by means of the flange 15 the tube 12 may be withdrawn and easily cleaned.

It will be seen that by means of this invention, a pipe has been provided which will assure a clean, dry smoke, without likelihood of the smoker drawing in a slug of foul tasting tarry matter, which often accumulates in the stem of an ordinary pipe.

10 It will further be seen that the parts near the bowl which usually become fouled, may be readily removed, cleaned out and replaced.

While I have disclosed a preferred form 15 of the invention, I do not wish to be strictly limited to the form shown, since changes may be made within the scope of the invention as defined in the appended claims.

I claim:-

20 1. In a smoking pipe, a bowl member with a bowl therein and having a stem near the upper open end thereof, said bowl member having a passage therein communicating with the lower end of said bowl and with said stem, said bowl member having a catch basin communicating with said passage, and a removable tubular member in said passage and communicating with said bowl and said stem and catch basin.

25 2. In a smoking pipe, a bowl member with a bowl therein and having a stem near the upper open end thereof, said bowl member having a passage therein communicating with the lower end of said bowl and with said stem, and a removable tubular member in said passage and in communication with said bowl and said stem and meeting the passage in said stem at a sub-

30 stantial angle.

35 3. In a smoking pipe, a bowl member having a bowl therein and having a stem near the open upper end thereof, said bowl member having a substantially vertical passage communicating with the lower end of said bowl and with a passage through said stem, a removable tubular member in the passage in said bowl and communicating with said bowl and with the passage in said

stem, and a removable catch basin below the lower end of said tubular member for receiving liquid from the latter.

4. In a smoking pipe, a bowl member with a bowl therein and having a stem near the upper open end thereof, said bowl member having a passage therein communicating with the lower end of said bowl and with said stem, a removable tubular member in said passage and communicating with said bowl and a passage in said stem, and means on one end of said tubular member to be engaged when it is desired to withdraw the latter.

5. In a smoking pipe, a bowl member with a bowl therein and having a stem near the upper open end thereof, said bowl member having a passage therein communicating with the lower end of said bowl and with said stem, a removable tubular member in said passage and communicating with said bowl and a passage in said stem, and means for positioning said tubular member to be engaged when it is desired to withdraw the latter.

6. In a smoking pipe, a bowl member with a bowl therein and having a stem adjacent its upper end with a downward passage in communication with the lower end of said bowl, a removable tubular lining member for said passage having an opening in its side in communication with said bowl, a removable catch basin below the lower end of said tubular member and in communication therewith.

7. In a smoking pipe, a bowl member with a bowl therein and having a stem near the open upper end thereof, said bowl member having a substantially vertical passage therein connecting the lower end of said bowl and a passage through said stem, a catch basin detachably secured to the lower end of said bowl member, a tubular member in the passage in said bowl member in communication with said catch basin and the lower end of said bowl and the passage in said stem, and means on said tubular member for positioning the same.

JOHN G. WINTJEN.
